UNITED STATES PATENT OFFICE

2,544,547

ELECTRICALLY HEATED FLOOR MAT

Charles A. Vogel, Huntington, W. Va.

Application March 21, 1949, Serial No. 82,585

1 Claim. (Cl. 219—19)

1

This invention relates to an electrically heated floor mat.

An important object of the invention is to provide a novel construction of a floor mat on which one can stand for the purpose of assuring comfort and protection despite the presence of cold, drafty or damp floors.

Another important object is to provide a mat of the character described which will provide even and uniform heat over its entire surface, can be made of low cost materials, and will be of high durability and practically indestructible.

Another important object is to provide a construction for a floor mat of the character described which can be adapted toward the manufacture of floor mats of any desired shape or size.

Still another object is to provide a construction, in a floor mat of the character stated, which will permit the elimination of unnecessary devices, such as thermostats, and the like.

Still another important object is to provide a floor mat construction as stated which will have a low current consumption, and which will be fully adapted to use not only in various types of businesses, but also in the home.

With the foregoing and other objects in view which will appear as the description proceeds, the invention consists of certain novel details of construction and combinations of parts, hereinafter more fully described and pointed out in the claim, it being understood that changes may be made in the construction and arrangement of parts without departing from the spirit of the invention as claimed.

Referring to the drawings

Fig. 1 is a top plan view of a floor mat constructed in accordance with the invention, with the top plate removed.

Fig. 2 is a longitudinal section taken on line 2—2 of Fig. 1.

Fig. 3 is a transverse section taken on line 3—3 of Fig. 1.

Fig. 4 is a wiring diagram.

Fig. 5 is a top plan view, with the top plate removed, of a modified form of the invention.

Fig. 6 is an enlarged section on line 6—6 of Fig. 5.

Fig. 7 is an enlarged section on line 7—7 of Fig. 5, portions being broken away.

Fig. 8 is a wiring diagram of the modified form of Fig. 5.

Referring to the drawings in detail, 5 is a bottom plate of any suitable material, such as tempered hard-board or the like, said bottom plate 5 preferably being quite thin but having the characteristic of rigidity. Marginally spaced around the periphery of bottom plate 5 are apertures 6 for a purpose to be described. At this point, it may be noted that the bottom plate 5 can be of any desired outer configuration, the substantially rectangular shape illustrated purely being one example of a possible shape for the floor mat. It could as well be round, or of any other suitable shape.

2

Extending longitudinally of the side edges of the bottom plate 5 are the elongated side strips 7, these having openings 8 spaced longitudinally thereof, said openings 8 registering with the openings 6 of the bottom plate.

The side strips 7, as will be observed, define between them a wide space extending from end to end of the floor mat, and this space is filled by a grid 9 of any suitable material, the side edges of said grid abutting against the inner side edges of the side strips 7, so that said grid 9 will have a snug, tight fit between the side strips. Thus, the inner surfaces of the side strips 7 will, after the grid 9 is fitted between said strips, close notches 10 formed in the side edges of the grid 9, said notches 10 being spaced longitudinally of the grid 9, and extending substantially the entire length of said grid.

In one end of the grid 9 I form an inwardly extended slot 11 opening from said end, and opening at its inner end into branch slots 12 that are extended in opposite directions at right angles to the slot 11. In the closed inner ends of the branch slots 12, I form enlarged recesses 13.

In the end portions of the grid 9, there are formed spaced openings 14.

A cord 15 is adapted to be plugged into the ordinary electrical outlet, and extends into the slot 11, as clearly shown in Fig. 1. The two sides of the cord 15 diverge at the inner end of the slot 11, and are respectively extended through the slots 12, to the enlarged recesses 13. In this connection, I fill the recesses 13 with solder 16, with the respective ends of the cord 15 being embedded in said solder.

Also embedded in the solder are the opposite ends of a length of resistance wire 17, thus providing an electrical connection between the resistance wire and the electric cord 15. Accordingly, when cord 15 is plugged into the ordinary electrical outlet, not shown, a circuit will be completed through the resistance wire 17.

Resistance wire 17, in being extended from one side of the cord 15, shown as the upper side in Fig. 1, is laced through the notches 10, so as to extend only over the top surface of the grid 9. After having been laced transversely of the grid, through the entire length of the grid, the resistance wire 17 is extended through an opening 17' formed in the grid 9, and is extended under the grid back to the other side of cord 15, shown as the lower side in Fig. 1.

A top plate 18 covers the electrical wiring, and can be formed of any material such as linoleum or the like. The top plate 18 is provided with marginally spaced openings, registering with the openings of the bottom plate, side strips, and the openings 14 in the ends of the grid. Rivets 19 are then used, extending through all the openings, so as to permanently secure the respective laminations of the device tightly together, in a permanent arrangement. It will be readily observed that a highly durable structure is thus

provided, said structure having the characteristic of rigidity, strength, and having no parts that can get out of order readily. In this connection, it will be observed that the cord 15 will be impossible to withdraw, since it will be so arranged as to have its ends embedded in the solder plugs 16, said plugs being of greater diameter than the breadth of the branch slots 12. Therefore, any pull upon the plug 15 will simply be transmitted to the solder plug, which will be firmly held against movement. Thus, there will be no tendency to pull the electrical connections apart.

Obviously, the floor mat formed as described can be of any desired ornamental appearance and outer configuration.

Referring now to the form of the invention illustrated in Figs. 5 through 8, a bottom plate 20 is provided with marginally spaced openings as in the case of the first form. Mounted upon the sides of the bottom plate 20 are the side strips 21, and mounted upon one end of the bottom plate are the short end strips 22 spaced apart at the center of the floor mat so as to provide a space for an electric cord in a manner to be described. The short strips 22 are provided with a plurality of openings spaced longitudinally thereof, and mounted on the other end of the bottom plate is a long end strip 22' also formed with longitudinally spaced openings. Thus, the floor mat has openings spaced marginally throughout its entire periphery, it being understood that the openings of the end strips at opposite ends of the floor mat will register with the openings formed in the bottom plate therebelow.

In the space defined between the respective side and end strips, a grid 23 is snugly fitted, and covering the grid is the top plate 24, also formed with peripheral marginally spaced openings registering with the openings of the side and end strips and bottom plate. Rivets are used as at 25 for the purpose of securing all portions of the device together in a permanent connection.

The cord 26 extends into the aforementioned space between the short end strips 22, the opposite sides of the cord diverging once inside the inner space, and being extended laterally toward the opposite side strips 21, and then being extended longitudinally of the respective side strips 21, through the entire length of the floor mat, said opposite sides of the cord 26 being extended along the inner surfaces of the respective side strips. At spaced intervals, the opposite sides of said cord are electrically connected at 27 to the resistances 28. Referring to Fig. 8, the resistances 28 are arranged in parallel, and thus a uniform heating arrangement is provided even though the mat illustrated in Fig. 5 is quite long. By reason of this construction, it is possible to provide a mat of any desired length or size, with the varicus resistances being connected in parallel so as to transmit heat uniformly.

As in the case of the first form of the device, the resistances are laced over the top of the grid, the side edges of the grid having notches as in the previous form for this purpose.

It will be understood that the number of resistances illustrated as being connected in parallel in the form of the invention illustrated in Fig. 5, can be varied as desired. Three have been illustrated purely for the sake of example.

It will be further noted that the grid in either instance is coated on both sides with a resinous insulating cement, before the grid and the side

strips are assembled between the top and bottom plates.

Through the selection of resistance wire of proper value, the current flow will be so regulated that the temperature of the mat can be predetermined in watts per square inch of mat surface so that thermostats, current breakers or fuses will be unnecessary.

Additionally, since the coefficient of expansion of the resistance wire due to temperature rise is known, the loops of the windings will be so spaced that one loop cannot make electrical contact with another.

It may be further noted that the temperature attained by the windings in the mat will be so low, and will be so distributed uniformly over the entire area of the mat, as to make impossible combustion of materials of which the mat is made.

20 What is claimed is:

In a floor mat a flat rigid bottom plate formed to an outer configuration and area corresponding to the overall area and outer configuration of the floor mat; a pair of side strips of flat, low formation supported upon the opposite longitudinal edges of said bottom plate and defining between them a shallow grid-receiving space; a grid completely filling said space and formed to a height corresponding to the height of said strips and having its top surface flush with the top surfaces of the strips, said grid having spaced notches formed upon its opposite longitudinal edges and said opposite longitudinal edges of the grid being in full contact with the side strips for closing of the notches when the grid is positioned in said space, the grid having at one end a slot opening inwardly from said end and branch slots extending laterally from the inner end of said slot, the branch slots having closed enlarged inner ends; conductive plugs seated in said enlarged inner ends of the branch slots; a resistance wire embedded at opposite ends in the respective plugs and laced through said notches; electric cords extending through the first-named slot and branch slots and embedded in said plugs; a top plate formed to the same area and outer configuration as the bottom plate and completely covering the grid and side strips; and fastening means rigidly connecting the top and bottom plates, side strips, and grid.

CHARLES A. VOGEL.
